UNITED STATES PATENT OFFICE.

ARTHUR DYMOCK, OF STOCKPORT, ENGLAND, ASSIGNOR TO AMERICAN CORETWINE COMPANY, OF BOSTON, MASSACHUSETTS, A CORPORATION OF MASSACHUSETTS.

PAPER TWINE.

1,165,953.

Specification of Letters Patent. Patented Dec. 28, 1915.

Application filed June 11, 1914. Serial No. 844,565.

To all whom it may concern:

Be it known that I, ARTHUR DYMOCK, subject of the King of Great Britain, residing at Stockport, in the county of Chester, England, have invented certain new and useful Improvements in Paper Twine; and I do hereby declare the following to be a full, clear, and exact description of the invention, such as will enable others skilled in the art 10 to which it appertains to make and use the same.

This invention relates to paper twine manufactured from a paper ribbon (or ribbons) which is twisted into twine in a damp 15 or wet state by suitable means and which may have incorporated in it a hemp or the like twine.

The object of the said invention is to improve the appearance and increase the 20 strength of such twine, to allow of the use of weaker paper than hitherto used in its manufacture, and to cheapen the means used for the said manufacture.

Heretofore the paper twine consisted of a 25 helically wound paper ribbon, which in some cases had a hemp or the like core, or of a paper ribbon twisted with its longitudinal edges curled inwardly, a hemp or the like core being in some cases provided central with the paper ribbon.

My improved paper twine consists of a paper ribbon which is first folded double, then again folded double and finally twisted, the hemp or the like core, when employed, being inside the first fold.

In the accompanying drawing which illustrates my improved paper twine, Figure 1 is a perspective view showing the formation of the said twine without a hemp or the like core, and Fig. 2 is a perspective view showing the formation of the said improved twine with a hemp or the like core. Fig. 3 is a sectional view on the line A—A, Fig. 2. Figs. 1 and 2 illustrate

a piece of finished twine which has been partially untwisted and unfolded in order to show its formation, and not a piece of twine in the process of manufacture. 45

Similar letters refer to similar parts throughout the several views. 50

Referring to Fig. 1, the paper ribbon *a* is first folded double as shown at *b*, then again folded double as shown at *c*, and afterward twisted as shown at *d*.

Referring to Fig. 2, the paper ribbon *a* 55 is first folded double with a hemp or the like core *e* inside the fold, then again folded double as shown at *c*, and afterward twisted as shown at *d*. The core *e* (see Fig. 3) is inclosed within the first fold, by the second 60 fold, so that it cannot slip out of the paper and be seen in the finished twine.

I claim:

1. A paper twine consisting of a paper ribbon folded approximately in the center 65 and refolded approximately in the center of the first fold and twisted.

2. A paper twine consisting of a paper ribbon folded approximately in the center and refolded approximately in the center 70 of the first fold and twisted, and of a core situated inside of the first fold of the paper ribbon.

3. A paper twine consisting of a paper ribbon folded double, approximately in the 75 center, a plurality of times and twisted.

4. A paper twine consisting of a paper ribbon folded double, approximately in the center, a plurality of times and twisted, and of a core situated inside the first fold of the 80 paper ribbon.

In testimony whereof I have affixed my signature in presence of two witnesses.

ARTHUR DYMOCK.
